VEHICLE WARNING SIGN

Robert K. Stortz, 16230 Cumberland Trail,
Brookfield, Wis. 53005

Filed Aug. 7, 1970, Ser. No. 24,369

Term of patent 14 years

Int. Cl. D29—02

U.S. Cl. D72—1

Fig. 1

Fig. 2

FIG. 1 is an elevational view showing one face of a vehicle warning sign embodying my new design, the opposite face being identical; and

FIG. 2 is a bottom edge view of the sign.

I claim:

The ornamental design for a vehicle warning sign, as shown and described.
